(57) **CLAIM**

The ornamental design for a line management device, as shown and described.

DESCRIPTION

FIG. 1 is a perspective view of the line management device of the present invention;

FIG. 2 is a top plan view thereof;

FIG. 3 is a bottom plan view thereof;

FIG. 4 is a first elevation view thereof;

FIG. 5 is a second elevation view thereof;

FIG. 6 is a left end elevation view thereof; and,

FIG. 7 is a right end elevation view thereof.

The broken lines shown represent portions of the line management device that form no part of the claimed design. Where the dot-dash broken lines abut the claimed surface it is understood that those broken lines represent an unclaimed boundary between claimed and unclaimed surfaces. None of the broken lines form any part of the claimed design.
